UNITED STATES PATENT OFFICE

2,422,300

RISER FOR BUBBLE CAP TRAYS

Hans C. Glitsch, Dallas, Tex., assignor, by mesne assignments, to Glitsch Engineering Company, Dallas, Tex., a partnership

Application May 26, 1945, Serial No. 595,981

3 Claims. (Cl. 261—114)

1

This invention relates to new and useful improvements in risers for bubble-cap trays.

The invention has particularly to do with the cylindrical risers which are used to support the bubble-caps and permit the passage of fluids through the trays and one object of the invention is to provide an improved riser of simple construction which may be mounted in the tray in a simple and efficient manner.

A particular object of the invention is to provide an improved riser of cylindrical form having its bottom or lower end arranged to be expanded and secured in the floor of the tray in a new and novel manner.

Another object of the invention is to provide an improved riser together with unique means of fastening the riser in the tray in a simple and inexpensive manner, whereby a fluidtight seal therebetween is obtained.

A construction designed to carry out the invention will be hereinafter described together with other features of the invention.

The invention will be more readily understood from a reading of the following specification and by reference to the accompanying drawing, wherein an example of the invention is shown, and wherein:

Fig. 1 is an elevation of a riser constructed in accordance with the invention and ready to be inserted in the floor section of a bubble tray,

Fig. 2 is a transverse, sectional view showing the riser secured in the floor section of a bubble tray,

Fig. 3 is a transverse, sectional view of a modified form and showing a bubble cap in position on the riser,

Fig. 4 is a horizontal cross-sectional view taken on the line 4—4 of Fig. 2, and

Fig. 5 is a partial sectional view of still another modification of the invention.

This application is a continuation-in-part of my co-pending application filed May 15, 1944, Serial No. 535,612.

In the drawing, the numeral 10 designates a bubble-cap riser which is substantially cylindrical and of uniform diameter. In making the riser, a strip of metal is rolled or otherwise formed to provide the cylinder, leaving a slight gap 11 between the adjacent edges of said strip. A longitudinal weld 12 is applied to this gap so as to overflow on the outer surface of the riser and not overflow on the inner surface thereof.

An important feature of the invention is terminating the weld 12 short of the bottom of the riser so as to leave an expansible skirt indicated generally by the numeral 13.

2

The floor 14 of the bubble tray is provided with a plurality of openings as is customary and one of these openings is indicated at 15. In the construction under discussion, the opening in the floor is initially made of such diameter that the marginal material may be extruded upwardly to form an annular surrounding collar 16 having an internal diameter of such amplitude as to snugly receive the riser 10 as is shown in Fig. 2. The collar 16 may be formed by a swaging or pressing operation and it is desirable that the inner lower bend of the collar indicated at 17 be rounded and smoothed. The riser is driven into the opening 15 so as to pass upwardly through the collar 16 until the lower edge of the riser is immediately below the bottom of the sheet 14. With the riser in this position, any suitable means is employed to expand the apron 13 into fluidtight contact with the opening 15 and the inner surface of the collar 16. This will provide a frictional engagement which will be sufficient to prevent the leakage of fluid between the collar and the riser or between the floor and the riser. However, to assure a rigid mounting of the riser, spaced welds 18 are provided between the top of the collar and the outer surface of the riser, one of these welds being placed at the bottom of the weld 12 and at the top of the open portion of the gap 11, whereby leakage at this point is prevented. This fastening or mounting of the riser is simple and comparatively inexpensive and may be expeditiously carried out. No bolts or other fastening devices are employed. If it should become necessary to replace the riser, the welds 18 can be dissolved and the riser driven downwardly and out of the floor.

In Fig. 3, I have shown another form of mounting in which the collar 16' is extruded downwardly from the floor 14. In this form it will be necessary to give the inner periphery of the collar and the opening 15, a curvature or flare indicated generally at 19, so that the skirt 13 may be expanded into intimate contact therewith in order to form a fluidtight joint. The riser is fastened by tack welds 20 at spaced intervals at the top of the opening 15.

In Fig. 5, I have illustrated another form of fastening the riser. It is obvious that many expedients may be employed in fastening or holding the riser against displacement. In this form, lugs or fingers 21 are upset outwardly from the wall of the riser just above the skirt 13 so as to rest upon the upper edge of the collar 16 or upon the floor 14 if used in connection with the form shown in Fig. 3. These lugs are spaced similarly to the welds 18. In forming the lugs, it is de-

sirable to only slightly upset the same so that a portion of the metal will remain in the opening 22 so as to partially close the same and obstruct the escape of fluids.

In Fig. 3, I have shown a bubble-cap 23 mounted on top of the riser merely for the purpose of illustration. It is obvious that many types of caps could be employed and the particular manner of fastening the cap is unessential.

It is pointed out that by reason of the expandable skirt, this portion of the riser may be swaged or expanded outwardly so as to form a very tight engagement with the floor sheet 14. Where the collar depends as does the collar 16' in Fig. 3, the swaging of the skirt 13 may even additionally swage said collar and thereby assure a tighter seal.

The riser is preferably made of stainless steel which is relatively expensive metal when compared to sheet steel. By rolling each riser separately, it is possible to use scrap metal and this greatly reduces the cost of the riser. It is quite difficult and impractical to roll or form a bead in a small, stainless steel riser, which may have a diameter of three inches. In rolling the riser, the vertical gap 11 is left, but by terminating the weld 12 above the lower end, the skirt 13 or bottom portion of the riser may be bent outwardly without unduly stretching the metal and rupturing it. While it is impractical to form a bead, the lugs 21 may be upset or extended outwardly without impairing the riser. The vertical opening or slot at the lower end of the weld 12 permits both expansion and retraction and thus the riser may be readily driven into an undersized opening.

The foregoing description of the invention is explanatory thereof and various changes in the

size, shape and materials, as well as in the details of the illustrated construction may be made, within the scope of the appended claims, without departing from the spirit of the invention.

5. What I claim and desire to secure by Letters Patent is:

1. The combination of a bubble tray floor having at least one circular opening surrounded by a collar of annular form and having a rounded edge on the inner portion of its annulus, a sheet metal riser member having a vertical gap extending from its top to its bottom, a weld closing said gap from its top downwardly and terminating short of the lower end of the gap, and a split annular skirt at the lower end of the member through which the gap extends, said skirt being expanded outwardly in fluid-tight contact with the rounded annulus.
2. The combination set forth in claim 1, and means secured to the riser member coacting with the skirt to hold said member against vertical displacement.
3. The combination set forth in claim 1, and spaced external projections on the riser member overhanging and engaging the collar for holding said member against downward displacement.

HANS C. GLITSCH.
